Attorney.

UNITED STATES PATENT OFFICE.

WELLINGTON ADAMS, OF ST. LOUIS, MISSOURI, ASSIGNOR TO THE ADAMS ELECTRIC COMPANY, OF SAME PLACE.

ELECTRIC SWITCH.

SPECIFICATION forming part of Letters Patent No. 285,778, dated October 2, 1883.

Application filed March 29, 1883. (No model.)

To all whom it may concern:

Be it known that I, WELLINGTON ADAMS, of St. Louis, in the county of St. Louis and State of Missouri, have invented certain new and useful Improvements in Switches for Electric Currents; and I do hereby declare that the following is a full, clear, and exact description thereof, reference being had to the accompanying drawings, and to the letters of reference marked thereon, which form part of this specification.

The present invention relates to improvement in devices for regulating the passage of electric currents from a main conductor to a working-resistance; and it consists in a switch by means of or through which more or less current may be allowed to pass without putting useless resistance into the work-circuit.

In the accompanying drawings, Figure 1 shows a side elevation, partly in section, of the regulator itself, together with its necessary connections. Fig. 2 is a detail view, showing the general construction of one of the traveling contact-brushes.

A represents a box, of any suitable construction, within which is placed a cylindrical tube, B, of vulcanite or other suitable insulating material. Above the tube B is placed a ring, C, of any suitable conducting material. Upon the ring C is placed a similar ring, D, of insulating material. The rings C and D alternate until any desired number—in this case three pairs—have been secured together, the whole forming a straight tube, E. To each one of the rings C is attached a wire, c, which should be of relatively high resistance, and the said wires are electrically connected to brushes F, that are in the form of cylinders, provided with yielding or elastic contact-springs extending from their sides, which construction adapts the cylinders to be moved longitudinally in the conducting-tubes G, which are slotted longitudinally, to allow the uninterrupted passage of a link or hook projecting from the traveling contact, to which projections the wires c are attached, as is more fully described in an application for Letters Patent filed by me March 26, 1883.

By means of a suitably-pivoted lever, H, the stem J is suspended within the tube E, and adapted to be moved vertically therein. To the lower portion of the stem J are secured disks K, which, together with said stem, are

of conducting material. They are secured the same distance apart as are the rings C D, and each disk is provided with four or more contact-springs, L, which are of oval form and secured to said disks with both ends inward, so as to be very flexible and capable of being moved in either direction without sticking or binding. From the upper end of stem J a wire, M, leads to the working-resistance. The conductor G being provided with a number of movable or traveling contact-brushes, F, each separately connected to a ring, C, and the disk-bearing stem J being in electrical connection with the working-resistance and a return or ground line, as the said stem is raised within its containing tube, the brushes or springs upon the disks will be brought into contact with any desired number of the rings C, and together form portions of one multiple-arc circuit, the conducting capacity of which may be thus increased or diminished.

Being arranged in multiple arc, as stated, the amount of current carried through the device will vary according to the number of disks and rings in operative contact, and by raising or lowering the hand-lever H a motor or other translating device connected to the wire M may be supplied with more or less current, as desired.

Having described my invention, I claim—

1. The combination of a tubular conductor and suitable contact-brushes, adapted to be traveled therein, with a series of fixed insulated conducting-disks separately connected to said traveling brushes, and means, substantially as described, for moving one or more of said contact-disks into the work-circuit in multiple arc, substantially as set forth. 90

2. The combination of frame A, tube B, and a series of insulated rings, C, with the stem J, provided with a series of disks, K, and contact-springs L, and means for moving said stem between the rings C and tube B, substantially as set forth. 95

In testimony that I claim the foregoing as my own I affix my signature in presence of two witnesses.

WELLINGTON ADAMS.
